WALTER VAN PATTEN STEIGER, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SNAP-SWITCH.

1,020,231.

Specification of Letters Patent. Patented Mar. 12, 1912.

Application filed December 3, 1908. Serial No. 465,755.

To all whom it may concern:

Be it known that I, WALTER VAN PATTEN STEIGER, a citizen of the United States of America, and residing at Bridgeport, in the county of Fairfield and State of Connecticut, have invented certain new and useful Improvements in Electric Snap-Switches, of which the following is a specification.

My invention relates to electric switch mechanisms more particularly applicable for use in key sockets and rotary snap switches, and one of the objects of my invention is to construct a simple but efficient switch mechanism, whereby a rotary motion 15 of the spindle in either direction will produce quick make and break movements of the switch lever.

In the accompanying drawings, Figure 1 is a vertical section of an incandescent electric lamp socket provided with my invention; Fig. 2 is a sectional perspective view of the main parts of the switch; Fig. 3 is a sectional view on the line 3—3, Fig. 5; Fig. 4 is a corresponding perspective view; Fig. 25 5 is a sectional view on the line 5—5, Fig. 3; Fig. 6 is a plan view of a rotary snap switch constructed in accordance with my invention; Fig. 7 is a sectional view on the line 7—7, Fig. 6; Fig. 8 is a sectional plan view.

Referring to Figs. 1 to 5, A is a one-piece insulating button of porcelain or other suitable material suitably chambered to receive the switch mechanism and having secured to one face the terminal screw shell S to receive and hold the lamp base. The usual central terminal T for the lamp base forms a continuation or portion of the bent plate t, (Fig. 5) secured to one side of the insulation and carrying the binding screw t¹. The 35 other terminal binding screw f is carried by the frame plate F of the switch mechanism. This frame plate has two ears 10 to provide bearings for the transverse operating spindle E having the usual key head or handle e by which the spindle may be rotated continuously in either direction. This frame F also carries a fixed spindle f¹, on which the switch bar or lever D is pivoted. The bottom of the screw shell S may be provided with clips s, Figs. 1 and 3, with which the outer end of this switch lever may make contact (Fig. 1) or break it (Fig. 3).

The spindle E has mounted upon it a cam H and upon its extreme end two curved flanges G, G¹, leaving intermediate breaks

or notches g. These flanges G, G¹ form retaining means to engage a finger d on the switch bar D, and hold the latter temporarily during the tensioning of the spring K, which is coiled around the fixed spindle f¹. This spring has its two legs k, k¹, adapted to bear on opposite sides of a projection d¹ on the switch bar or lever D, and these two legs of the spring are continued beyond the projection d¹, so as to lie in the path of the cam H, on opposite sides thereof, as shown in the drawings.

Assuming the switch to be closed as illustrated in Fig. 1, which shows the positions of the parts when the lever D has just snapped into engagement with the clips s to close the circuit, the finger d (Fig. 2) will then be in a position to ride on the outside of either retaining flange G, G¹, depending upon which way the key is turned. 75 Rotary motion of the key spindle in either direction will then bring the cam H around to press on the leg k¹ of the spring K. Let us assume that the key is turned in the direction of the arrow, Figs. 1 and 2, the result will be that the cam H pressing upon the leg k¹ of the spring while the leg k of the spring is held back by the projection d¹ of the switch lever, will tension the spring, so that when the rotation of the spindle E 80 in the direction of the arrow, Fig. 2, brings the finger d to the notch g, the spring K will cause the lever D to make a quick break at s. A further rotation of the spindle in either direction will cause the cam H to 85 leave the leg k¹ of the spring and to act upon the leg k, but meantime the finger d having passed through the notch g will be engaged with the inner face of the flange G (or G¹) and will be held back in the position shown in Figs. 3, 4 and 5, until the finger d comes opposite the next notch g (Figs. 3 and 4), out of which it snaps under the action of the meantime tensioned spring. 95

In Figs. 6 and 7 I have shown my invention applied to a rotary surface single pole snap switch, A¹ being the insulating base with the two contact fingers C, C¹, to which the wires are to be connected, and with an 105 operating spindle E¹ and turn button e¹. This spindle, which is mounted to turn in a frame F¹, secured to the base, carries a cam H¹ to act upon the legs of a spring K, and also carries a part G², the same as the 110

part G, G¹ of Figs. 1 to 5 to act on a suitable finger upon the switch lever D¹. This switch lever has spring fingers d², d², to contact with the fingers C and C¹ and therefore close the circuit in one position of the lever D¹, and to make a double break when in the other position of the lever. In Figs. 6 and 7, the lever is shown in the open circuit position.

10 I claim as my invention—

1. An electric switch mechanism, comprising a frame, an oscillating switch lever and two-legged spring in combination with a rotary operating spindle capable of continuous rotation in either direction, and having a cam to act on either leg of the spring and having also curved flanges to temporarily detain the lever.

2. An electric switch mechanism, comprising a frame, an oscillating switch lever having a finger and a projection and a two-legged spring to bear on the latter, in combination with a rotary operating spindle

capable of continuous rotation in either direction, and having a cam to act on either leg of the spring and having also curved flanges to act upon the finger on the switch lever.

3. An electric snap switch, comprising a frame and an oscillating switch lever, in combination with spring means to act on the lever, and a rotary operating spindle capable of continuous rotation in either direction, said lever carrying a cam to act on the spring and detents to act on the lever, whereby rotary motion of the spindle is converted into an oscillating motion of the switch lever with snap action, substantially as described.

In testimony whereof I have signed my name to this specification, in the presence of two subscribing witnesses.

WALTER VAN PATTEN STEIGER.
